DIMMITT ROSS LOVEJOY, OF NEW YORK, N. Y., ASSIGNOR TO LOVEJOY DEVELOPMENT CORPORATION, OF NEW YORK, N. Y., A CORPORATION OF NEW YORK.

COIL-WINDING METHOD AND APPARATUS.

Application filed September 25, 1925. Serial No. 58,570.

The object of this invention is to furnish means for the production on a manufacturing scale of a particular kind of induction coil. The coil to be produced has the character of a helix with an odd number of sections in each turn, the adjacent sections of adjacent turns being radially staggered.

According to my present invention the wire is first crimped into sections of the desired length, and is then wound in a cylindrical or polygonal form so that the sections will become staggered as above described.

A further feature of the invention involves a first winding on a crimping form in which the wire is bent and crimped into the shape it is desired to have it assume, the crimping forming an even number of sections per revolution and then transferring the crimped and formed wire onto an assembling cylinder of a diameter such as will require an odd number of such sections to encompass it, to the end so that the crimping can be done all in one direction and yet have the final result staggered in the desired manner.

The invention will be better understood by reference to the accompanying drawings, in which:

Figure 1 is a plan view of an apparatus suitable for carrying out my invention, and

Figure 2 is a transverse sectional view taken on line 2-2 of Figure 1;

Figure 3 is a similar section on the line 3-3 of Figure 1;

Figure 4 is a similar section on the line 4-4 of Figure 1;

Figure 5 is a longitudinal section taken on the line 5-5 of Figure 3;

Figures 6 and 7 are sectional views of details;

Figure 8 shows a modification of the crimping form;

Figure 9 shows a part of a cylindrical inductance coil wound according to my invention;

Figure 10 shows a part of a polygonal coil wound according to my invention.

In a copending application, Serial No. 732,021, I have described a cylindrical inductance coil of the low loss type which has each turn crimped into an odd number of sections, the sections of one turn being radially staggered with the adjacent sections of the adjacent turns, the wires crossing each other with an obtuse angle at the end of the

sections, while the sections lie in parallel arcs between crossings. Such a coil is shown in part in Figure 9, which has exterior sections *a*, alternating with interior sections *b*, in any given turn.

Referring to Figure 1, there is shown at 1, a rotatable chuck driven by pulley 2. An arbor 3 held in the chuck supports the stationary hub 4 and on its outer end secured to it, face plate 5, which has radial slots 6. There are an even number of these slots, in this case six, and in each slot is radially guided a carrier 7. In each of these carriers a pin 8 is slidably mounted. Secured to the face plate 5 is a crimping form 9, the bolts 10 holding these parts together having extensions 11 projecting outwardly from the face of the form.

The pins 8 are moved back and forth by wedge guides 12 and 13, (see Figures 3, 6 and 7,) the pin 12 causing the pins to be pushed back until their front ends are flush with the face of the spider for the purpose of allowing the wire, which is shown at 14, to lay onto the face of the form 9, and the wedge guide 13, causing the pins to be pushed forward thru the carrier until they overhang the wire as it rests on the form. The form 9 is shown with six arc-shaped peripheral sections, three of which 15, are of a less radius than the alternating three 16. On the stationary hub 4 which is prevented from rotation by an arm 17, (see Figure 1) is a cam 18 and on the inner ends of the carriers 7 are rollers 19 adapted to bear upon this cam, while springs 20, attached to the pins 21 hold the rollers in firm contact with the face of the cam. As the face plate rotates, the cam serves to push the carriers outward during the time the pins 8 are retracted, and to allow the springs 20 to pull the carriers inward during the time the pins 8 are projected over the wire. An angle plate 22 may be used to aid the springs 20 by impinging on the outer face 100 of the rollers 19 at the right place to insure a definite crimping action.

Facing the crimping mechanism just described, is an assembling form 23 held by a rotatable chuck 23'. The circumference of this assembling form must be equal to an odd number, of the sections 15-16, either greater or less than the number of sections in the crimping form 9, thus, if the crimping form 9 has six sections, as shown, the assem-

bling form 23 may have for example a circumference seven-sixths of the circumference of the crimping form 9, so that it will require seven of the sections formed on the crimping form to encircle the assembling form. The object of this is to bring the sections of greater radius on one turn next to the sections of lesser radius on the adjacent turns, and thus produce the desired staggered effect. The front of the assembling form 23 is in line with the front of the crimping form. The axes of the two forms are therefore offset as shown by the dotted center lines in Figure 1. The form 23 is comprised of a metallic tube split longitudinally as shown as 24 and mounted at each end on cone-faced plugs 25 and 26 which in turn are carried by a central arbor 27. A slight movement outward of the cone 25 allows the split tube 23 to collapse sufficiently to permit the easy removal of the coil from the form. The cone plug 25 has a peripheral flange 25' the interior of which has seven, or any other odd number of notches 28, which causes the flange 25' to act as an internal gear to the six or any even number of pins 11 which project from the crimping form. By this means the relation of the circumferential speeds of the crimping form 20 and the winding form are made such that an even number of sections encircling the crimping form will, by the relative, slower or relative faster movement of the winding form result in an off number of sections encircling the latter.

In operation a wire 14 is led over a guiding pulley 30 and wound on the crimping form by the rotation of the arbor 1. At a point beyond where the wire first contacts with the form, the pins 8, pushed outward by the wedge 13, are thru the action of the cam 18 and springs 20, brought down onto the wire at a point adjacent the shoulder on the form between the inner and outer sections and is thus crimped or bent to conform to the shape of the form, the plate 22 insuring the pressing home of each pin in turn. As shown in Figure 3 there are two of these pins for each of the sections of lesser radius. After the form has turned a half revolution, the pins 8 are slid back by the wedge 12 so that the wire is released. The crimped wire after another half turn is guided by guide 31 onto the winding form. The end of the wire is secured to the winding form by any suitable means as for example a rubber band 32, and the successive turns are pushed together by the hand of the operator as each turn comes around until the desired number of turns have been wound, when the machine is stopped and the wire again secured by a rubber band or the like at the outer end. Before releasing the coil flat strips 33 (see Figure 9) are inserted in the spaces between the inner and outer sec-

tions to hold the turns in place until cords 34 can be tied around the crossings. After the strips 33 are in place, the cone plug 25 is moved slightly outward and the cylinder 23 will then collapse sufficiently to allow the coil to be taken off the form, the form being removed from the chuck 23' for this purpose or the chuck itself moved a sufficient distance to the right.

The crimping form may be polygonal instead of circular and Figure 8 shows a partial view of such a form. In this case, the number of sides is also even and the equivalent of the inner and outer radii is attained by making alternate sides of the polygon longer than the intermediate sides. When a wire is wound on such a form and transferred to a polygonal winding form, having an odd number of sides, a coil having the characteristic such as shown in Figure 10, will result.

While I have shown a practicable method of winding inductance coils with staggered sections, I do not wish to be limited to the specific mechanism shown, as there are many parts of the apparatus that may be changed to equivalent means or omitted altogether, and still embody the essential features of my invention as set forth in the following claims.

I claim:

1. The method of winding helical wire coils, comprising, winding and crimping the wire in the form of a turn with an even number of sections per turn and then winding it in helical form, the perimeter of which is equal to an odd number of said sections.

2. The method of winding helical wire coils comprising winding the wire on a form having a perimeter divided into an even number of sections whose distances from the center are alternately long and short and then assembling said wire into a coil in which adjacent portions of successive turns are at alternately long and short distances from the center, said wire passing from one distance to the other an odd number of times per turn.

3. The method of winding helical wire coils comprising, winding the wire onto a crimping form having a perimeter divided into an even number of sections with alternate sections radially displaced, and then removing the wire from the said form and winding it on an assembling form, the circumference of which is equal to an odd number of the said sections whereby the adjacent sections of adjacent turns, will be radially displaced.

4. The method of winding helical wire coils comprising, winding the wire onto a crimping form having a perimeter divided into an even number of sections transferring the wire from the said form and winding it on an assembling form, the circumference of

which is equal to an odd number of said sections and rotating the first and second forms at axial speeds inversely proportional to their circumferences whereby the adjacent sections of adjacent turns of the finished coil will be radially displaced.

5. In apparatus for winding wire coils, the combination comprising, a rotatable shaping form, means associated with said form for crimping the wire in sections with alternate sections displaced radially and an assembling form having a circumference equal to an odd number of said sections, said

assembling form being geared to the said shaping form so as to run at an axial speed 15 inversely as the circumferences of the two said forms.

6. The method of winding coils, which comprises bending the wire at intervals to define sections, and thereafter winding the 20 bent wire into a helix, each turn of which contains an odd number of sections and the successive sections of which are radially staggered.

DIMMITT ROSS LOVEJOY.
